UNITED STATES PATENT OFFICE.

HARRY M. FOSTER, OF MINNEAPOLIS, MINNESOTA.

SACK CUTTING, FOLDING, AND SEWING MACHINE.

1,187,057.

Specification of Letters Patent. Patented June 13, 1916.

Application filed December 29, 1914. Serial No. 879,513.

To all whom it may concern:

Be it known that I, HARRY M. FOSTER, citizen of the United States, resident of Minneapolis, county of Hennepin, State of Minnesota, have invented certain new and useful Improvements in Sack Cutting, Folding, and Sewing Machines, of which the following is a specification.

The object of my invention is to provide a machine in which the blank for a fabric sack, such as used for flour or other cereals, can be cut, folded and sewed on one end and one side in a continuous operation as the blank passes through the machine.

15 A further object is to provide a machine of simple, economical construction and one in which the described operations can be effected by means of comparatively few parts.

20 Other objects of the invention will appear from the following detailed description.

The invention consists generally in various constructions and combinations, all as hereinafter described and particularly pointed 25 out in the claims.

In the accompanying drawings forming part of this specification, Figure 1 is a side elevation of a machine embodying my invention, Fig. 2 is a longitudinal vertical sectional view of the same, Fig. 3 is a plan view of the machine, Fig. 4 is an end elevation, Fig. 5 is a detail view, illustrating the means for delivering and feeding the sack at the end of the machine, Figs. 6 and 7 are detail 30 sectional views, illustrating the operation of the cutting roll and the means for feeding the blank between the belts preparatory to sewing one end of the sack, Fig. 8 is a detail view of the device employed for cutting 35 the thread between adjoining sections, Fig. 9 is a sectional view on the line $x-x$ of Fig. 8, Fig. 10 is a sectional view on the line $y-y$ of Fig. 8, Fig. 11 is a detail view of the ratchet mechanism for operating the 40 intermittently moving reel, Fig. 12 is a detail elevation of a portion of one side of the machine, showing the driving means for the feed rolls.

In the drawing, 2 represents the frame of 45 the machine. 3 is a shaft, horizontally mounted therein and preferably lengthwise of the machine and having a pulley 4 for a belt connection with some suitable source of power.

50 5 is a horizontal shaft, mounted transversely of the machine and driven from the

shaft 3 by a suitable worm gearing 6. A beveled gear 7 is mounted on the shaft 5 on the opposite side of the machine and is geared to an upright shaft 8 which, in turn, 55 is geared at 9 to a horizontal shaft 10 that is mounted in the upper portion of the machine frame. A feed roller 11 is mounted on the shaft 10 in frictional engagement with a similar roller 12 that is spring pressed 60 toward the roller 11 in the usual way and the shaft 10 has a driving connection through a belt 13 and a sprocket wheel 13' with a feed roller 14 beneath which is a similar roller 15. This sprocket wheel 13' 65 is driven through a suitable gearing from the shaft 10. A bolt of cloth 16 is supported in suitable brackets 17 and the free end of the cloth is fed between the rollers 14 and 15 and is allowed to drop and lie loosely 70 upon a plate or table 18. From this table the cloth passes over the feed roller 11 and down between it and the roller 12, as indicated in Fig. 2.

A gear 19 is mounted on the shaft 10 and 75 meshes with a gear 20 on a transverse shaft 21. A mutilated gear 22 is mounted on the shaft 21 in position to engage the teeth of a pinion 23 on the shaft of a cutting roll 24 that is provided with a cutting edge 25 extending spirally on the roll and co-operating 80 with a stationary blade 26 to sever the cloth as it passes between them. Evidently the cutting roll is operated at predetermined 85 intervals, governed by the position of the teeth on the gear 22. Normally this roll is held out of its cutting position by means of a notched cam 27 that is engaged by one arm 28 of a bell crank that is pivoted at 29 and has its second arm 30 in position to be engaged and tripped by the pin 31 on the gear 22. Normally the arm 28 will engage the shoulder of the recess of the cam 27 to hold the cutting roll in the position indicated in 90 Fig. 1, a spring 32 being provided for yielding 95 supporting the arm 28 in engagement with the cam. Just before the teeth of the gear 22 come into mesh with the teeth of the pinion 23 the pin 31 will engage the arm 30 and trip the bell crank, releasing the roll 100 and allowing the gear 22 to operate it and cut the sack blank. During the time that the next blank is being fed forward, the cutting roll will remain inoperative to again be released and perform the cutting operation 105 when the teeth of the gears 22 can come into engagement with the pinion 23. The period 110

of operation of this cutting roll governs, of course, the width of the blank and the sack.

A cam 33 is mounted on the shaft 5 in position to engage an arm 34 mounted on a rock shaft 35 which is journaled in transverse bearings in the machine frame and is provided with upwardly extending arms 36 having forked upper ends which straddle screws 37 adjustably mounted in the rear edge of a pusher bar 38 which is arranged transversely of the machine and slidably on rods 39 supported on each side of the machine frame. The screws 37 have stops 40 and 41 upon opposite sides of the forked ends of the arms 36 so that when the said arms are rocked, the screws will be reciprocated to operate the pusher bar. The forward edge of the bar is preferably tapered, as indicated at 42, and is on a level substantially with the space between the rows of the feed belts 43 and 44, so that when the sack blank drops down in its vertical position in front of the feed belts, the movement of the pusher bar will press a fold of the blank in between the feed belts and at this time the cutter roll will sever the blank and allow it to be drawn in between the belts to complete the folding operation and where it will be engaged by the sewing machine. The feed belts operate horizontally, one above another, and a plurality of fingers 45 are mounted between the belts over which the bag blank is fed. These feed belts are operated in any suitable manner, preferably by means of a worm gearing 46 driven through a belt 47 from the drive shaft 3.

A sewing machine 48 is mounted on one side of the machine frame and operated through a belt 49 from the shaft 3 and stitches across one end of the folded blank, as shown plainly in Fig. 3, to form the bottom of the sack. A shaft 50 is geared at 51 to the shaft 5 and extends horizontally of the machine and is geared at 52 to a shaft 53 which extends diagonally across the machine and is geared at 54 to a shaft 55 on which a thread cutting knife 56 is loosely mounted and is provided with oppositely arranged cutting blades 57 for severing the thread between the sacks. A spring 58 is coiled on the shaft 55 and has a bearing at one end on a pin 59 that is mounted in the knife disk. An eccentric 60 is secured on the shaft 55 and a disk 61 is engaged by said eccentric as said shaft revolves and raised thereby sufficiently to disengage a lug 62 on said disk from a stop 63 on the box of the shaft 55. The knife disk is provided with a pin 64 which normally engages the disk 61 and is held thereby against premature movement. When, however, the disk 61 is raised and disengaged from the stop 63, the pressure of the spring will revolve the disk 61 and the knife a half revolution, or until the lug 62 strikes the stop

63 on the underside of the shaft bearing, whereupon the movement of the parts will be arrested. During this half revolution of the knife, one of the blades 57 will sweep past the stationary cutter 65 and sever the thread between the adjoining sacks.

By means of the above described mechanism the sack blank is cut from the bolt of cloth, folded once lengthwise and sewed across one end to close that end and form the bottom of the sack. I will now proceed to describe the mechanism for reversing the position of the sack to increase the capacity of the machine and sewing the longitudinal edge of the sack to complete it.

66 is a cam, mounted on the shaft 50 and 67 is a plunger having an anti-friction bearing on the periphery of said cam and slidably in a guide on the machine frame and having a link connection 68 with an arm 69 on a shaft 70. The shaft 70 has a gear 71 thereon meshing with a pinion 72 carried by a head 73 in which a plurality of reel arms 74 are mounted and adapted to pass between the fingers 45 and pick up the sack blank therefrom, accidental displacement of the blank being prevented by means of suitable brads or points 75 on the reel arms and the fingers 45. Intermittent movement is imparted to this reel by means of a ratchet mechanism 76 of ordinary construction, premature movement of the ratchet being prevented by a dog 77 connected by a link 78 with a lever 79 that is tripped by means of a lug 80 on the cam 66. As this cam revolves, movement will be transmitted through the ratchet mechanism to revolve the reel and gather up the sack blanks.

At the end of the machine frame a right angled extension 81 is provided. A feed table 82 is mounted to slide transversely of the main frame of the machine upon cross rods 83 and lengthwise of the extension 81, a spring 84 being mounted on one of said cross rods for the purpose of holding the feed table in its retracted position. Said table preferably consists of a series of parallel rods and a plate 85 at its forward edge provided with fingers 86 which are adapted to enter annular grooves 87 formed in a lower feed roll 88. The upper roll 89 has feed belts 90 co-operating with those of the lower roll to receive the partially sewed bag from the feed table and advance it over the plates 91, which have fingers 92 projecting into the annular grooves in the lower feed roll. The plates 91 project beyond the discharge end of the feed belts to deliver the completed sack out of the machine. A shaft 93 is mounted in the extension 81 of the frame and is driven through a belt 94 from the driving shaft 3 and has a driving connection through a belt 95 with a worm gearing 96 through which the feed rolls 88 and 89 and the belts 90 are operated. The

shaft 50 has a cam 97 thereon for operating the lever 98 which has a pin and fork connection at 99 with the frame of the feed table 82, as shown in Fig. 4, and at a pre-determined point in the operation of the machine this lever 92 will be rocked to move the feed table toward the feed belts 90 and deliver the partially sewed sack thereto. The shaft 93 has a belt drive 100 with a second sewing machine which I will designate by the same reference numeral with the addition of the exponent "a," this machine operating to stitch the longitudinal seam of the sack as it is fed between the belts 90. A knife similar to the one described is also mounted near the sewing machine 48^a and I will designate it by the same reference numeral as the knife previously described with the addition of the exponent "a." This knife is driven through a shaft 101 that is geared to the shaft 50 and to the shaft of the knife disk, as shown in Fig. 4.

In the operation of the machine, the cloth is cut and folded and delivered by the initial feed belts 43 and 44 upon the fingers 45 and is picked up by the revolving reel and delivered with one end of the sack stitched upon the rails of the feed table 82. In making this delivery, the reel will invert the bag so that the unsewed longitudinal edges will be adjacent the outer edge of the feed table and will pass to the belts 90 in position to be engaged and sewed by the second sewing machine 48^a. The mechanism will be so timed that while the reel fingers on one side of the axis of the reel are picking up the sack and delivering it upon the feed table, the fingers on the other side of the reel axis will engage the next sack to deposit it upon the feed table as soon as the first one has been delivered by this table to the secondary feed belts 90.

The sacks will be fed through the machine a few inches apart, the thread being severed by the knife in the initial feeding means, so that when each sack reaches the fingers projecting beyond the feeding means, it will be free to be turned to an inverted position by the revolution of the reel. This picking up of each sack from the initial feeding means and delivering it in an inverted position to the secondary feeding means increases the capacity of the machine as it hastens the movement of the sacks and prevents them from becoming clogged or piled up at the point where the right angle turn is made in the delivering means to provide for sewing the side of the sack. The reel, of course, can be operated at a suitable speed to insure removal of each sack from the fingers 45 before the delivery of the next sack to these fingers, and by the time the first sack is delivered to the feed table of the secondary feeding means, the arms

of the reel on the other side of its axis are in position to pick up the next sack.

I prefer to invert the sack blank after sewing the bottom thereof for two reasons. First, it enables me to use a right hand sewing machine, being a duplicate of the one used for sewing the end; whereas, if the direction of movement of the blank should be changed and the side of the blank sewed up to form the sack without inverting the blank, it would be necessary to use a left hand machine and this would involve considerably additional expense. Furthermore, sufficient time must be provided to change the direction of movement of the blank and perform the sewing operation and this I obtain by picking up the blank after it has been folded and sewed on one end and delivering it upon the transversely operating carrier out of the path of the next blank.

In various ways the details of construction herein shown and described may be modified and still be within the scope of my invention.

I claim as my invention:

1. The combination, with a means for delivering the web in a substantially vertical position, means for severing the web transversely to form a sack blank, and means operating substantially midway between the free end of the web and said severing means to fold the sack blank transversely of the web and lengthwise of the sack, feed belts between which the folded blank is moved, and means for sewing one end of the folded blank during such movement.

2. The combination, with means for severing a bag fabric web and folding the bag blank, of means for feeding the folded blank and sewing two of its edges together, and means for inverting the blank and feeding and sewing the other two edges together.

3. The combination, with means for severing a web of bag fabric and means for folding the bag blank longitudinally along the middle line thereof, of means for feeding the folded blank and sewing one end thereof, and means for inverting the blank and feeding and sewing the longitudinal edges of the blank together.

4. The combination, with means for folding a fabric bag blank lengthwise along the middle line thereof, and means for sewing one open end of the folded blank, of revolving means for inverting the folded blank and means for feeding the blank and sewing the longitudinal edges thereof together to complete the sack.

5. The combination, with means for folding and feeding the blank and sewing one end thereof, of a revolving reel having fingers to gather up the blank, a feed table whereon the inverted blank is deposited by

- said fingers, and means operating transversely of said first named feeding means for feeding the blank on said table and sewing the longitudinal edges thereof.
- 5 6. In a machine of the class described, means for feeding a folded bag blank, a revolving reel having pick-up fingers, and means for operating it intermittently, said fingers engaging the sack blank, a table whereon the blank is deposited in an inverted position by said fingers, and means operating transversely of said first named feeding means for feeding the blank from said table and sewing one side thereof.
- 10 7. The combination, with means for feeding a folded sack blank transversely, of means for feeding the blank lengthwise thereof, a device interposed between said feeding means for inverting the blank during its passage from one feeding means to the other, and sewing devices provided in connection with said feeding means for sewing one end and the longitudinal edges of the blank.
- 15 8. The combination, with means for feeding a sack blank folded lengthwise along the middle line thereof, said feeding means having fingers forming continuations thereof upon which the folded blank is delivered, a second feeding means operating transversely with respect to said first named feeding means, sewing devices in connection with both said feeding means, and a revolving reel interposed between said feeding means and having fingers adapted to pass between the fingers of said first named feeding means and gather up the blank thereon, and a feed table in connection with said second named feeding means having fingers upon which the blank is deposited 40 in an inverted position by the fingers of said reel.
- 45 9. The combination, with means for feeding a bag blank folded longitudinally along the middle line thereof, of a sewing machine for sewing across the ends of the folded blanks as they are fed past it, a knife for severing the thread between adjoining blanks, a second feeding means operating transversely with respect to said first named 50 feeding means, means for inverting the blank during its passage from one feeding means to the other, and a sewing machine and thread cutting means provided in connection with said second feeding means. 55
10. The combination, with an initial feeding means for a bag blank and a device for sewing one end thereof and cutting the thread, of a secondary feeding means operating transversely with respect to said initial feeding means and adjacent thereto, a second sewing device and means for picking up the partially sewed blank and inverting it and delivering it to said secondary feeding means, and sewing devices for 60 sewing the longitudinal edges of the blank.
- In witness whereof, I have hereunto set my hand this 18th day of December, 1914.
- HARRY M. FOSTER.
